UNITED STATES PATENT OFFICE.

FRED E. BRADFIELD, OF DAVENPORT, IOWA.

DESIGN FOR AN AUTOMOBILE.

54,589.

Specification for Design.

Patented Mar. 9, 1920.

Application filed October 20, 1919. Serial No. 332,113. Term of patent 7 years.

To all whom it may concern:

Be it known that I, FRED E. BRADFIELD, a citizen of the United States, residing at Davenport, in the county of Scott and State of Iowa, have invented a new, original, and ornamental Design for Automobiles, of which the following is a specification, reference being had to the accompanying drawings, forming part thereof.

In the drawings,—

Figure 1 is a front view of an automobile showing my new design.

Fig. 2 is a side view of the automobile shown in Fig. 1.

I claim:

The ornamental design for an automobile, as shown.

FRED E. BRADFIELD.
